UNITED STATES PATENT OFFICE.

JOHN W. BUTTERFIELD, OF COLUMBUS, OHIO.

MECHANISM FOR CONVERTING ROTARY TO RECIPROCATING MOTION.

SPECIFICATION forming part of Letters Patent No. 605,218, dated June 7, 1898.

Application filed January 19, 1898. Serial No. 667,147. (No model.)

To all whom it may concern:

Be it known that I, JOHN W. BUTTERFIELD, a citizen of the United States, residing at Columbus, in the county of Franklin and State of Ohio, have invented a certain new and useful Improvement in Mechanism for Converting Rotary to Reciprocating Motion, of which the following is a specification.

My invention relates to the improvement of mechanism for converting a rotary into a reciprocating motion; and the objects of my invention are to provide a comparatively simple and reliable mechanism of this character by means of which a steady and uniform reciprocating motion is generated from a rotary motion, to so construct and arrange the parts of the same as to reduce both friction and power, and to otherwise produce a simple, reliable, and effective device of this kind which can be employed for moving the beds of printing-presses or for other similar purposes. These objects I accomplish in the manner illustrated in the accompanying drawings, in which—

Figure 1 is a side elevation of my improved mechanism. Fig. 2 is a similar view showing the driving-arms and movable parts in a different position from that indicated in Fig. 1. Fig. 3 is a plan view. Fig. 4 is a rear side elevation. Fig. 5 is a central transverse section on line $z-z$ of Fig. 1. Fig. 6 is a vertical section taken between the pinion-wheel and one of the driving-arm heads, and Fig. 7 is a detail sectional view on line $z-z$ of Fig. 2.

Similar numerals refer to similar parts throughout the several views.

In the construction of my improved mechanism I employ a main frame 1, which is preferably of the general oblong form shown and which may consist, as shown, of an upper horizontal arm 2, a similar lower arm 3, curved end arms 4, and a central longitudinal arm 5. Within this main frame and adjacent to the forward side of the arm 5 I provide a vertically-movable rack carrying oblong frame 6, of which 7 represents the vertical end bars. The frame 6 is provided at each end with upper and lower rearwardly-projecting guide-lugs 8, the latter being shown more clearly in Fig. 5 of the drawings, and through each pair of these guide-lugs passes loosely a vertical rod 9, which is fixed in the frame 1. Secured

to front side of the upper and lower horizontal bars of the frame 6 are horizontal and parallel rack-bars, which are indicated, respectively, at 10 and 11, and the teeth of one of said rack-bars projecting toward the teeth of the other.

Formed or secured upon the front face of each of the curved end arms or bars 4 of the main frame 1 is a track-segment, these segments being indicated at 12 and 13 and being, as indicated more clearly in Fig. 7 of the drawings, of a dovetailed form in cross-section.

14 represents opposing driving-arms, each of the latter having formed with its outer end an enlarged head 15, the latter being formed with an outwardly-projecting inwardly-turned C or crescent-shaped flange 16. Projecting from said head is a pin 17, which is concentric with the inner wall of the C-flange 16, said pin preferably having an enlarged outer end or head 18. Each of the heads 15 has its rear side provided with a grooved channel of a dovetailed form, as indicated at 15^a in Fig. 7, this channel embracing loosely the adjoining correspondingly-shaped tracks 12 and 13. At a point 19 in the inner end portion of each of the driving-arms 14 said arm is fulcrumed to the central bar 5 of the frame 1, while said inner end portions of said driving-arms terminate in opposing gear-segments 20, the teeth of which are adapted to mesh one with the other, as shown. Between the gear-segments 20 and the fulcrum-points 19 the bars 14 have pivoted thereto the upper ends of short link-bars 21, the lower ends of which are similarly connected with lugs 22 on the lower bar of the frame 6.

23 represents an operating-pinion or gear-wheel which is mounted upon a suitable journal power-shaft 24, which extends at right angles with the direction of the lengths of the rack-bars and driving-arms. The driving-pinion 23 has its circumference of equal length with the racks 10 or 11 and has formed in its otherwise-toothed periphery at the proper point a rounded recess 25, which is adapted, as indicated in the drawings, to receive alternately during the operation of the mechanism the projecting pins 17 of the driving-arm heads.

In the drawings I have shown the frame 1

secured to the under side of the machine bed-plate 26, which may be the bed-plate of a printing-press or a part of any other machine or device to which a reciprocating motion is 5 to be imparted.

It will be observed that the diameter of the pinion-wheel 23 is somewhat less than the distance between the toothed surfaces of the racks 10 and 11.

10 As indicated in section in Fig. 6, in full lines in Fig. 5, and in dotted lines in Fig. 2, I provide the inner side of the pinion 23 with a rearwardly-projecting journaled roller 27.

In order to illustrate the operation of converting the rotary motion, suitably imparted 15 to the shaft 24, to a reciprocating motion of the plate or frame part 26, I will assume that the parts are in the position indicated in Fig. 2 of the drawings—that is, that the driving-

20 arms are in horizontal alinement with each other, that the driving-arm heads are central on the tracks 12 and 13, and that the projecting pin 17 of that head which is on the track 12 is within the recess 25 of the pinion 23. Ro-

25 tary motion being now imparted in any suitable manner to the shaft 24, in the direction indicated by the arrow in said Fig. 2, it is obvious that the head 15, which is on the track 12, will be carried upward on said track until

30 the teeth of the pinion are thrown into engagement with the under side of the upper rack-bar 10. Owing to the connection of the gear-segments 20 it is obvious that the driving-arm head 15 at the opposite end of the machine will likewise be carried upward on the track 13. In the movement thus imparted 35 to the driving-arms it is obvious that the same, owing to their fulcrum connection with the lower portion of the frame 6 through the

40 bars 21, cause a lowering of said frame 6 until the upper rack-bar 10, which is carried thereby, is in proper alinement with the teeth of the pinion to receive the latter. The rotary motion of the shaft being continued, it is

45 obvious that the engagement of the teeth of the gear-wheel with the upper rack must result in carrying the connected frames 1 and 6 in the direction indicated by the dotted arrow in said Fig. 2, and consequently in a cor-

50 responding movement of the bed-plate 26, with which said frame 1 is connected. When the rack-bar has passed out of engagement with the pinion-wheel, it is obvious that the motion of the frames in the direction of the dotted arrow will be continued by the engagement of the pin 17 of that head 15 which is on the track 13 with the recess 25 of said pinion. The continued rotation of the shaft

55 results in the head on the track 13 traveling downward until the teeth of the pinion are ready for engagement with the teeth of the lower rack 11, the latter having been raised through the upward pull of the bars 21 during said downward movement of the heads.

60 65 As the head on the track 13 passes the center thereof it is obvious that the movement

of the main and rack-carrying frames will be reversed and that this reversed movement will continue until the pinion has passed over the opposite end of the lower rack and the 70 head on the track 13 has passed the center of the latter in its upward movement. During the engagement of the pins 17 of the heads with the pinion-recess it will be seen that a proper engagement of said pinions and pins will be assured, from the fact that the guide-rollers 27 of the pinion are traveling against the inner walls of the head-flanges. 75

It will be observed that through the rotary motion of the shaft a desirable reciprocating 80 motion of the frames and bed-plate 26 is imparted and that this is accomplished without undue friction of the parts.

Having now fully described my invention, what I claim, and desire to secure by Letters 85 Patent, is—

1. In a mechanism for converting rotary to reciprocating motion, the combination with a frame 1 having curved end tracks, driving-arms fulcrumed to said frame and having a 90 segmental gearconnection at their inner ends, heads on the outer ends of said driving-arms, said heads having a sliding connection with said tracks, and a pin projecting from each of said heads, of a vertically-movable frame 95 6, an upper and lower rack-bar carried thereon, bars 21 jointedly connecting said frame 6 and driving-arm a power-shaft and a pinion-wheel on said shaft having a peripheral recess, the teeth of said pinion adapted to engage alternately with said rack-bars, the pins 100 of said driving-arm heads adapted to engage as described with said pinion-recesses and a guide projection on said pinion adapted to travel in guideways on said heads, substantially as and for the purpose specified.

2. In a mechanism for converting rotary to reciprocating motion, the combination with a frame 1, a curved track on each end thereof, opposing driving-arms fulcrumed to said 110 frame 1 and having a segmental gear connection at their inner ends, and a head on each of said driving-arms, a guideway on each of said heads said heads having a sliding connection with said end tracks and a projecting 115 pin on each of said heads, of a frame 6 vertically movable in said frame 1, bars 21 jointedly connecting said driving-arms and said movable frame, a rotating shaft 24, a pinion carried thereon, the latter having a peripheral 120 recess and a guide-roller projecting therefrom adapted to travel in the guideways of the arm-heads, substantially as and for the purpose specified.

3. In a mechanism for converting rotary to reciprocating motion, the combination with a frame 1, a curved track on each end thereof, opposing driving-arms fulcrumed to said frame 1, driving-arm heads having a sliding connection with said tracks, a curved flange 125 on each of said heads, and a pin projecting from each of said heads concentric with the

curve of said flange, of a vertically-movable frame 6 connected with said frame 1 and having a jointed connection with the driving-arms, a rotary shaft 24, a pinion 23 thereon, 5 a peripheral recess in said pinion adapted to receive as described said head-pins and a roller projecting from said pinion and adapted

to travel against said head-flanges, substantially as and for the purpose specified.

JOHN W. BUTTERFIELD.

In presence of—

C. C. SHEPHERD,
CHARLES CASE.
